CLAIM

The ornamental design for an oven control panel, as shown and described.

DESCRIPTION

FIG. 1 is a perspective view of an oven control panel showing a first embodiment of our ornamental design;

FIG. 2 is a front view thereof;

FIG. 3 is an enlarged view of the oven control panel shown in FIG. 1, without unclaimed surrounding environment;

FIG. 4 is an enlarged view of the oven control panel shown in FIG. 2, without unclaimed surrounding environment;

FIG. 5 is a front view of an oven control panel showing a second embodiment of our ornamental design;

FIG. 6 is a front view of an oven control panel showing a third embodiment of our ornamental design;

FIG. 7 is a front view of an oven control panel showing a fourth embodiment of our ornamental design; and

FIG. 8 is an enlarged front view of FIG. 5;

FIG. 9 is an enlarged front view of FIG. 6; and,

FIG. 10 is an enlarged front view of FIG. 7.

Where included, broken lines showing environment or structure are for illustrative purposes only and form no part of the claimed design.
